DESIGN FOR A FEATHERED BROOCH

Louis Israel, New York, N. Y.

Application June 25, 1937, Serial No. 70,048

Term of patent 3½ years

To all whom it may concern:

Be it known that I, Louis Israel, a citizen of the United States of America, residing in Manhattan, county of New York, and State of New York, have invented a new, original, and ornamental Design for a Feathered Brooch, of which the following is a specification, reference being had to the accompanying drawing, forming part thereof, wherein,

The rear portion of the brooch has a conventional pin and catch closing.

I claim:

The ornamental design for a feathered brooch, substantially as shown, and described.

LOUIS ISRAEL.
